(57) **CLAIM**

The ornamental design for a slide projector base for camera lens and strobe, substantially as shown and described.

DESCRIPTION

FIG. 1 is a perspective view of a slide projector base for camera lens and strobe, according to an embodiment;

FIG. 2 is a rear view of the slide projector base for camera lens and strobe, according to the embodiment;

FIG. 3 is a front view of the slide projector base for camera lens and strobe, according to the embodiment;

FIG. 4 is a left side view of the slide projector base for camera lens and strobe, according to the embodiment;

FIG. 5 is a right side view of the slide projector base for camera lens and strobe, according to the embodiment;

FIG. 6 is a top view of the slide projector base for camera lens and strobe, according to the embodiment; and,

FIG. 7 is a bottom view of the slide projector base for camera lens and strobe, according to the embodiment.

The broken lines shown in the figures are included for the purpose of illustrating portions of the article and form no part of the claimed design.
